Primary Examiner—Ted Shooman*Assistant Examiner*—Nanda Bondade*Attorney, Agent, or Firm*—Gary M. Nath; Nath & Associates**[57] CLAIM**

The ornamental design for a container for two detergents, as shown and described.

DESCRIPTION

FIG. 1 is a front view of a container for two detergents showing our new design;

FIG. 2 is a top view thereof;

FIG. 3 is a rear view thereof;

FIG. 4 is a bottom view thereof;

FIG. 5 is a right side view thereof;

FIG. 6 is a left side view thereof; and,

FIG. 7 is a perspective view thereof.

The broken line showing on FIGS. 1-3 and 5-7 is for illustrative purposes only and forms no part of the claimed design.
